TYPEWRITING MACHINE

William F. Helmond, West Hartford, Conn., assignor to Underwood Elliott Fisher Company, New York, N. Y., a corporation of Delaware

Application April 20, 1938, Serial No. 203,066

9 Claims. (Cl. 248—25)

This invention relates to devices for supporting and releasably holding a typewriter or similar machine in place on a supporting structure.

An object of the invention is to provide a rugged hold-down device adapted for economic manufacture, having complementary latching parts readily attachable to the typewriter and the supporting desk respectively, serving to securely hold the typewriter against accidental dislodgement.

Another object is to provide a releasable hold-down device, the sound isolation characteristics of which render same particularly adaptable for use in conjunction with a resilient typewriter foot having sound-absorbing characteristics, the combination thus affording adequate means for supporting and holding the typewriter, at the same time minimizing the transmission of typewriter noises into the supporting structure of the machine.

One embodiment of the hold-down device, preferably employed at each of the forward feet of the typewriter, provides a conveniently accessible finger-piece actuatable to release the catch by a downward pressure applied by the thumb of the operator, while the fingers may lift the typewriter from the foot retaining sockets until entirely free of the hold-down device.

Other objects and advantages will hereinafter appear.

This is a continuation in part of my co-pending application, Serial No. 675,254 filed June 10, 1933, now Patent No. 2,118,085, issued May 24, 1938.

In the accompanying drawing:

Figure 1 is a side elevational view showing a typewriter resting on a supporting structure or desk board and illustrating the typewriter feet and hold-down device in cross section.

Figure 2 is a side elevation illustrating the use of the hold-down device and resilient feet in cooperation to retain the typewriter on the tilted board of the usual typewriter desk.

Figure 3 is a plan view of a desk board illustrating the preferred arrangement of foot-receiving sockets and the associated hold-down devices.

Figure 4 is a detail perspective view in quarter section, of the associated resilient foot and one form of the hold-down device shown in Figure 1.

Figure 5 is a vertical sectional view of a resilient foot and a modified form of hold-down device, and

Figure 6 is a detail perspective view of the de-

vice shown in Figure 5, the resilient foot being shown in quarter section.

A typewriter 10, resting on a table or baseboard 11, is illustrated in connection with the resilient feet and hold-down device. Each foot includes 5 a rubber portion 12 which forms the base of the foot and a felt portion 13. The rubber portion is reduced in diameter to form a neck 14 and an upwardly-facing shoulder 15. The felt portion or collar 13 fits the neck 14 and is seated upon 10 the shoulder 15, the latter being made concave, by being beveled downwardly from its outer edge, as shown. By the concavity of the shoulder 15, the tendency of the felt collar to spread under the load of the typewriter is resisted. The felt 15 collar 13 overtops the neck 14 of the rubber portion 12 which is thereby, for the purpose of minimizing the transmission of noise, spaced from the machine. The felt collar 13 is surrounded by a cap 16 which embraces the periphery of the collar, and thereby cooperates to resist the spreading of the latter.

The top of the cap 16 bears against the machine-surface to which the foot is attached by means of a headed screw 18. Cooperating with 25 a shoulder 19 of said screw is a seat 20, which is counterbored from the bottom of the rubber portion 12. The screw 18 also has a shoulder 21 which bears against the bottom of the cap 16 when the foot is attached to the machine, it being noted that the shoulder 19 at the screw-head is preferably spaced from the seat 20 for minimizing the transmission of machine noises to the table 11. The bottom of the rubber portion 12 may be concave. The screw 18 has a thread 22 30 received in the typewriter 10.

For retaining the typewriter against lateral displacement, the table is provided with cups or sockets 23, in which the feet of the typewriter are set, the sockets being secured to the table 40 by bolts 24, and arranged as shown more clearly in Figure 3. In each form of hold-down device, same is associated with the front feet of the typewriter, the purpose of the hold-down device being primarily to hold the machine 10 from tumbling off the base-board 11 as the latter is tilted 45 into the typewriter desk 41, Figure 2.

The hold-down device of the first form shown in Figures 1 and 4, and indicated generally by numeral 25, has for each front foot of the typewriter a fixed hasp or plate 27 having an eye 28 and adapted to be secured to the typewriter by means of the screw 18 which passes through a hole in said plate. A dowel 29 keeps the plate from turning, and thereby keeps its eye 28 in 50 55.

alignment with a hook-forming tongue 30 of a catch 31 formed as shown more clearly in Figure 4. Said catch 31 is swingable between latched and released positions indicated respectively by the full outline and dotted outline in Figure 1. For fulcruming the catch and detenting it in either position, there underlie the cup 23 for the front foot, a pair of superposed plates 32 and 33, both plates extending forwardly from the cup 23 and being secured, together with said cup, to the table 11 by the bolt 24, each plate having a hole through which the bolt passes. The plates 32, 33 are prevented from turning by a dowel-screw 34 passing through holes in the plates, the screw-head being cleared by a hole in the cup 23.

The upper plate 32 is formed to present an inverted V-shaped notch 36 facing the lower plate 33, the forward end of said upper plate 32 passing through an aperture 37 of the catch 31 which, as indicated in Figure 4, forms polygonal pivot-key 35 having a pivoting edge 38 fulcrumed in the notch 36. Paralleling said pivoting edge 38 is a bottom edge 39 of the catch 31, said bottom edge bearing upon the top of the lower plate 33. The plate 32 may be made of spring metal, so that the plates 32, 33 are resiliently pressed together when fastened down on the table 11. Thus, the pivot-key 35 is clasped by resilient pressure between said plates 32, 33 and forms the pivot for the swinging of catch 31. It will be noted that the resilient pressure exerted by plate 32, coacting with the polygonal pivot-key 35, yieldably holds the catch 31 to either one of its positions which are determined by abutment of the respective faces of key 35 with opposite sides of the V-shaped notch 36. As the catch 31 is swung to either position, there is momentarily a slight increased separation of the plates 32, 33 as the lower edge 39 is thrown between opposite sides of the fulcrum formed by the notch 36. The forward end of the lower plate 33 may be bent to overlie the free end of the upper plate 32 to form a buttress 42 to prevent excessive flexure of the upper plate 32 as it cooperates with the catch 31 in holding the typewriter in tilted position when the latter, housed in a typewriter-desk 41, is swung with its table 11 to the retired position, Figure 2. The typewriter-desk 41 includes the conventionally indicated linkage 43 associated with the tilting and raising of the table 11. The foot-parts 12, 13 and 16 are preferably made uniform in dimensions, and, to compensate for the absence of the hold-down parts at the rear feet, the cups 23 for said rear feet may rest upon shims 44.

For handling the composite foot as a unit which includes either the cap 16, or both said cap and the hasp-plate 27, the parts are held together by the screw 18. For this purpose, the cap 16 alone, as for the rear feet, is threaded over the screw-thread 22, or both the cap and the hasp-plate 27, as for the front feet, are threaded over said screw-thread. The screw-thread 22 is undercut to form a shoulder 45 serving with the shoulder 21 of the screw to retain the cap 16 and the hasp-plate 27, after the latter two parts have been threaded past the shoulder 45. The undercut or groove permits the screw to be turned without turning parts 16, 27. At the screw-receiving opening in the hasp-plate 27 and a similar opening in the cap 16, the parts may individually be thin enough to thread over the screw-thread 22 without being provided with a screw-thread themselves. It will be seen that either the front foot including the hasp 27 or the

rear foot without said hasp, may, by the described arrangement, be handled as a unit when detached from the typewriter.

The eye 28 of the hasp-plate 27 is formed in a tongue 46 of said plate, which slopes outwardly and downwardly from the top of the foot to extend in spaced parallelism with the catch 31 when the latter is in its effective position. It will be noted that the catch 31, in effective position relatively to the hasp-plate 27, serves adequately to hold the typewriter against dislodgment and, the hasp-plate 27 and catch 31 are nevertheless out of contact with each other to thus prevent transmission of sound through the hold-down device. 15

The hasp-plate 27 preferably is constructed of a separate piece as shown but may be a part of the typewriter frame. Thus, in a sense, the catch 31 is engageable with the typewriting machine, although specifically engaging the hasp-20 plate carried thereby.

The second or modified form of a hold-down device illustrated in Figures 5 and 6 will now be described, this form presenting substantially a similar arrangement to that embodied in the first 25 form but incorporating certain other features and advantages as will hereinafter appear. In this form the cap 50, which resists spreading of the felt portion 13 of the resilient foot, is extended so as to provide a hasp 51 having an eye 30 52 for reception of the releasable catch of the hold-down device, indicated generally by numeral 54. The cap 50 has a circumferential flange which embraces substantially the entire periphery of the felt portion 13 to prevent excessive 35 distortion of same under load of the typewriter, the depending flange being directed outwardly at one region in the periphery to form the hasp 51. The hasp 51 is secured to the typewriter by the screw 18 which, as in the first form, serves also to hold the resilient foot in place on the typewriter. Cap 50 has a dowel 53 seating in the typewriter 10 to prevent rotation of the cap and thus maintain alignment of hasp 51 with the catch 54.

A cup or socket 55 is secured to the baseboard 11 by a screw 56 which also serves to secure a 45 lower or base plate 57 and an upper plate 58 to the baseboard, each of said plates having an aperture admitting a countersunk portion 59 of the cup 55, accommodating the head of screw 56 as shown more clearly in Figure 5. A dowel screw 60 serves to prevent displacement of the lower plate 57, the upper plate 58 having an aperture clearing the head of said screw.

The upper plate 58 acts as a spring and is accordingly formed of resilient material bent to 55 provide an inverted V-shaped notch 61 adjacent the free end of the plate. The lower plate 57 forms an incline or cam 62 substantially opposite the notch 61, the free end of plate 57 being overturned at 63 so as to overlie the free end of the upper plate.

The catch 54 may be fabricated of flat stock, being bent intermediate its ends into a zigzag or reverse bent form defining a medial portion 65 at 65 one end of which, a hook-forming tongue 66 is provided and, at the opposite end, a polygonal pivot-key 67 defined by an aperture 68. The projecting portion of the upper plate 58 is disposed within the aperture 68 so that the pivot-key 67 is retained in notch 61 to cooperate between the notch and the incline or cam 62. Resilient plate 58 exerts a downward pressure on the pivot-key 67, pressing the pivot-key against lower plate 57, thereby in cooperation with cam 75.

62, tending to rotate the key in a counter-clockwise direction which serves to yieldably hold catch 54 in its normal position, which position is defined by the abutment of the catch with the overturned portion 63.

The hasp 51, as shown in the drawing, is preferably constructed integral with the cap 50, the latter being a separate piece attached to the typewriter. However, the hasp 51 in the organization forms a part of the typewriter and thus in a sense, the catch 54 is engageable with the typewriting machine, although specifically engaging the hasp 51 carried thereby.

As shown more clearly in Figure 6, the intermediate portion 65 of the catch is extended laterally to provide a finger-piece 70 which, by manual pressure applied downwardly thereto, causes the catch 54 to be swung to released position as shown in dot-and-dash outline in Figure 5, in which position the tongue 66 is swung clear of the hasp 51 and the typewriter may be easily lifted from the sockets 55. In this regard, it is to be noted that the arrangement of the catch 54, particularly the finger-piece 70 thereof, facilitates releasing and raising the typewriter from its supports in that the thumbs of the operator may engage the finger-pieces 70 of each hold-down device while the operator's fingers raise the typewriter.

A feature embodied in this form of the hold-down device is of advantage in placing the typewriter on the table 11, the arrangement being such that the catch 54 will snap into engagement with the hasp 51 as the typewriter is lowered into place, a lip 71 of the hasp being disposed angularly so as to press the catch-tongue 66 downwardly and rearwardly until same snaps into engaging position within the hasp-eye 52. In this regard, the pivotal mounting of the catch 54 so as to swing the tongue 66 downwardly and rearwardly, makes for an easy retraction of catch 54, the direction of retraction being in accord with the lowering of the typewriter-carried hasp 51, with the rear feet of the typewriter already seated in the sockets. It will also be noted that, with the catch 54 in normal latched position, the parts thereof adjacent the hasp 51 are spaced therefrom to prevent any transmission of sound vibrations through the hold-down device and thus, in conjunction with the resilient typewriter foot, will serve to substantially isolate any sound vibrations within the typewriter occurring during the use of the machine, although adequately holding the typewriter in place on the baseboard 11 as the latter is tilted into the typewriter desk 41.

From the foregoing, it will be seen that there is provided, in several embodiments, a novel hold-down device of simple and rugged construction adapted for economic manufacture, and of such form as to be capable of fabrication of sheet metal. It will also be seen that either embodiment of the hold-down device is particularly adapted for use in conjunction with resilient, sound absorbing feet of a typewriter, the combination thus serving to retain the typewriter in position on its baseboard during the use thereof, the parts being so organized as to prevent any transmission of sound vibrations from the machine to the supporting structure, also providing a conveniently releasable latch which, upon tilting the typewriter into the desk, holds same in place.

The invention is not confined to the exact embodiments shown in the drawing nor to the pre-

cise details of construction illustrated therein, but certain modifications and changes may be made within the spirit or scope of the invention as expressed in the appended claims.

What is claimed as new is:

1. A hold-down device for typewriting machines, including a swingable catch having a pivot-key, the lower portion of said key acting upon an element presenting a flat surface to said key, a leaf-spring adapted for mounting on said element for yieldable engagement with said key, said spring presenting a transverse notch for retaining said key and forming a pivot bearing with said element for said catch, said spring co-acting with said key and said element to yieldably hold said catch in machine-holding position and permit said catch to be swung to releasing position.

2. A hold-down device for releasably holding a typewriting machine on a baseboard, including two plates one above the other, adapted for attachment flatwise to the baseboard, at least one of said plates being resilient for yieldable movement relatively to the other plate, a machine-engageable catch having a pivot-key disposed transversely between said plates, one of said plates presenting a transverse notch for retaining said key and forming a pivot bearing for said catch with the other said plate, said plates co-acting with said key to yieldably hold said catch in engaging position and permit said catch to be swung to releasing position.

3. A hold-down device for releasably holding a typewriting machine on a baseboard, including a base plate attachable to the baseboard, a resilient plate superposed on said base plate, a machine-engageable catch having a pivot-key disposed transversely between said plates, said resilient plate presenting a transverse notch for retention of said key in operative association with said plates, said key having a pivoting edge edge fulcrumed in said notch, another edge of said key bearing on said base plate, each of said plates co-acting with said key to yieldably hold said catch in machine-engageable position and permit swinging of said catch to releasing position.

4. A hold-down device for releasably holding a typewriting machine on a baseboard, including a base plate attachable to the baseboard, a resilient plate superposed on said base plate, a machine-engageable catch having an aperture defining a pivot-key disposed transversely between said plates, said resilient plate projecting through the aperture of said catch and presenting a transverse notch for retention of said key in operative association with said plates, said key having a pivoting edge fulcrumed in said notch, another edge of said key bearing on said base plate, each of said plates co-acting with said key to yieldably hold said catch in machine-engageable position and permit swinging of said catch to releasing position.

5. A sound-isolating fastening device for holding a typewriting machine releasably on a baseboard, including a pair of plates one above the other, adapted for attachment to the baseboard, at least one of said plates being resiliently yieldable relatively to the other plate, one plate having a V-shaped transverse notch facing the other plate, a machine-engageable catch having a pivot-key portion clasped on edge between said plates, said key portion having a pivoting edge fulcrumed

- in said notch and also having an edge spaced from said pivoting edge to bear on said other plate, said spaced edge being thrown to opposite sides of the pivoting fulcrum as the catch is swung between machine-releasing and machine-catching positions, the resilient plate yielding to permit the swinging of said catch, said notch cooperating with said key portion to limit the swing of said catch to either position.
10. 6. A hold-down device for releasably holding a typewriting machine on a baseboard, including a base plate attachable to the baseboard, a resilient plate superposed on said base plate, a catch including a pivot-key carrying a machine-engageable tongue, said catch being swingable toward said base plate to release said tongue, said resilient plate presenting a transverse notch straddling an upper edge of said key and pressing thereon, said base plate presenting a cam 15 to the other edge of said key, whereby said catch is yieldably held in machine-engageable position.
15. 7. A hold-down device for releasably holding a typewriting machine on a baseboard, including a base plate attachable to the baseboard, a resilient plate superposed on said base plate, a catch formed of sheet metal having an apertured portion presenting a pivot-key and carrying a machine-engageable tongue, said catch being swingable toward said base plate to release said tongue, said resilient plate presenting a trans- 20
- 25
- 30

and pressing thereon, said base plate presenting a cam to the other edge of said key, whereby said catch is yieldably held in machine-engageable position, said base plate having an upwardly projecting portion forming a stop for engagement of said catch.

8. A hold-down device for typewriting machines, comprising, in combination, a swingable catch including a polygonal pivot-key, two superposed plates having portions embracing said pivot key and forming a journal therefor, at least one of said plates being resilient to yield in swinging said catch, said plates coating with said pivot-key to yieldably hold said catch in machine-engageable position.

9. A fastening device for holding a typewriting machine having a detachable resilient foot, to a baseboard having a detachable socket in which said foot sets; comprising a releasable catch adjacent said foot and extending from the baseboard to the machine, plates underlying said socket and swingably mounting said catch on the baseboard, means securing said socket and mounting plates together on the baseboard, said resilient foot having an expansible body portion, a cap overlying and embracing said foot-body portion restraining expansion thereof, said cap having an eye-piece engageable by said catch, and means securing said foot and said cap to the machine.

WILLIAM F. HELMOND.
